UNITED STATES PATENT OFFICE

169,437

PIANO

Helmut Grotrian-Steinweg, Braunschweig, Germany, assignor to Grotrian, Helfferich, Schulz, Th. Steinweg Nachf. OGH, Braunschweig, Germany, a corporation of Germany

Application July 18, 1952, Serial No. 20,672

Term of patent 14 years

(Cl. D56—9)

To all whom it may concern:

Be it known that I, Helmut Grotrian-Steinweg, a citizen of Germany, residing at Zimmerstrasse 24, Braunschweig, Germany, have invented a new, original, and ornamental Design for a Piano, of which the following is a specification, reference being had to the accompanying drawing, forming part thereof.

In the drawing:

Fig. 1 is a front perspective view of a piano showing my new design.

Fig. 2 is a rear perspective view thereof.

I claim:

The ornamental design for a piano, as shown.

HELMUT GROTRIAN-STEINWEG.
